UNITED STATES PATENT OFFICE.

JOSEPH G. HAYES, OF INDIANAPOLIS, INDIANA, ASSIGNOR TO HAYES BROTHERS, OF INDIANAPOLIS, INDIANA, A CORPORATION OF INDIANA.

DRAIN-PIPE.

1,114,881.

Specification of Letters Patent.

Patented Oct. 27, 1914.

Application filed February 12, 1912. Serial No. 676,958.

To all whom it may concern:

Be it known that I, JOSEPH G. HAYES, a citizen of the United States, residing at Indianapolis, in the county of Marion and State of Indiana, have invented certain new and useful Improvements in Drain-Pipes, of which the following is a specification.

My invention relates to drain pipes and its object is to provide means whereby a pipe of this class may be tested after the pipe sections have been joined and a flooring or pavement laid over the same and to provide means, coöperating with an expansible plug employed for the purpose of closing the pipe to permit the latter to be tested, for enabling a worn plug or plugs of different sizes to be effectively employed to close the opening of the pipe.

With these ends in view, my invention is embodied in preferable form in the construction hereinafter described and illustrated in the accompanying drawing.

In these drawings, the view shown is a central vertical section through the pipe and the expansible plug used in connection therewith.

According to the usual mode of constructing and laying soil pipes and of testing them, the main soil pipe 1 is laid up to the joint 2. Then a plug consisting of an expansible member is inserted in the end of the pipe 1 so as to close the same and the pipe tested by introducing a fluid therein to detect the presence of leaks and then the trap is connected to the drain pipe section 3 by means of a suitable permanent joint.

To effect the foregoing operation, it is obvious that access must be had to the soil pipe at the joint and to provide for such access the laying of the floor or pavement above the pipe joint must be delayed until the testing operation can be carried out.

In my invention, means are provided to enable the testing to be carried out after the joint has been sealed and the flooring or pavement laid, which is effected by providing a plug receiving vertical intake section in the drain pipe proper or trap and accessible through its open upper end even after the flooring or pavement has been completely laid. To this end the drain pipe trap section 3 is provided with a vertical intake section 4. For the purpose of closing this

trap to permit the testing of the pipe by the introduction of fluids or otherwise an expansible plug 5 is provided, consisting preferably of a rubber ring mounted upon a screw-operated metal expander 6. This plug is adapted to be inserted in the upper end of the trap and to be forced tightly against the inner wall of the intake section above the seal portion of the trap, for the purpose of closing the latter.

A catch basin is secured to the upper end of the drain pipe and is provided with a central cylindrical portion adapted to abut against and form a continuation of the trap proper. The catch basin is provided in its upper edge with an annular recessed portion forming a seat for a cover.

The upper part of the trap section is divided into two vertical portions 7 and 8 of different diameters, the upper section being of the greater diameter. Projecting interiorly of the trap section at the lower end of the upper section 8 is a shoulder 9 against which the expansible rubber ring constituting the plug is adapted to be forced, and against which the plug abuts for the purpose of providing a tight joint between the trap section and the plug and affording a resistance against which the pressure of the expanding member can act to force the ring laterally against the wall of the trap. The upper end of the intake section is open and is accessible from above the floor or pavement in which the trap is laid whereby the plug may be readily inserted after the flooring or pavement has been completed and the testing operation thus performed without delaying the building operation or without necessitating the removal of a portion of the floor above the permanent joint at 2 for the purpose of obtaining a test of the pipes. At the lower end of the small section 7, a similar interior shoulder 10 is provided.

When the plug has become worn so that it will not fit tightly against the wall and shoulder of the upper section 7, the plug is passed through said upper section into the lower section and against the lower shoulder 10, and is then expanded against the lower shoulder, and thereby a tight closure may be obtained even with a worn plug, thus avoiding the necessity of discarding the plug when so worn that it will not fit the upper

section. The double section also permits the employment of plugs varying slightly in diameter in their original condition.

Having thus described my invention what I claim is,

- 5 1. A drain pipe having a trap provided with a vertical intake section with an open end accessible from above the floor or pavement under which it is laid, said intake section having an upper portion terminating at its lower end in an interior shoulder and having another portion of smaller diameter below said first portion and terminating in an interior shoulder, both of said shoulders being intermediate the open intake end and the lower end of said intake portion, said portions of the intake section being adapted to receive and coöperate with an expansible pipe closing member for sealing the outer 10 end of said pipe for testing purposes, substantially as described.
- 15 2. A drain pipe having a trap provided with a recessed seat for a cover and with a vertical intake section open at its upper end

and accessible at said end from above the floor or pavement in which the trap is laid, said trap communicating at the end opposite to the intake end with a suitable soil pipe, said vertical intake section composed of two adjoining vertical cylindrical sections both above the seal portion of the trap and below the cover seat and of different diameters, the section of smaller diameter being below the other, each having an interior shoulder at the lower end thereof against which an expansible plug is adapted to be forced for the purpose of closing the trap and its communicating pipe at the intake end to permit testing, substantially as described.

In witness whereof, I, have hereunto set my hand and seal at Indianapolis, this 2nd day of January, A. D. nineteen hundred and twelve.

JOSEPH G. HAYES. [L. s.]
